UNITED STATES PATENT OFFICE.

LESLIE W. CLAYBOURN, OF CINCINNATI, OHIO.

HEATER.

1,318,969.

Specification of Letters Patent. Patented Oct. 14, 1919.

Application filed March 9, 1917. Serial No. 153,733.

To all whom it may concern:

Be it known that I, LESLIE W. CLAYBOURN, a citizen of the United States, residing at Cincinnati, in the county of Hamilton and 5 State of Ohio, have invented certain new and useful Improvements in Heaters, of which the following is a specification.

My invention relates to heaters of solids in plate or sheet form, and is especially 10 adapted for heating plates having a comparatively low fusing point, or which comprise parts having a low fusing point, and is exemplified as employed in heating printing plates.

15 I have found that in certain character of work it is desirable to heat the solid, usually in plate or sheet form, to such degree of temperature as to be near the fusing point of the material of which the solid or a part of 20 the same is composed, but to avoid liquefaction of the same, and it may be instances that it is desirable to heat the material sufficiently to render the mass of the material spongy, but avoid liquefaction of the same 25 in whole or in part.

Instancing the use of the invention it may be stated that it may be employed in heating printing plates, and as an illustration of the purpose of the invention, it may be 30 stated that printing plates may be constructed to comprise a printing-shell on which the printing lines are formed, this printing-shell usually being electrodeposited metal, such as copper, which has a fusing 35 point of 1900 degrees Fahrenheit, deposited on the matrix in electro-plating, and a backing on which the printing shell is supported. The backing is usually fixed to the printing-shell by being poured thereon in melted condition.

40 This backing may, for example, be a mixture or composition of lead, tin and antimony, in the proportion of ninety pounds of lead to five pounds each of tin and antimony, the fusing point of the mixture or 45 composition being approximately 600 degrees Fahrenheit. It may be instances as an example but not as a limitation, that it is desirable to subject the printing plate to 50 a temperature of approximately 500 degrees Fahrenheit for a duration of a given time, which may be instances as from five to seven minutes, to reduce the backing material of the printing plate to the desired

state for operation thereon, instanced as a 55 spongy or compressible condition of the backing material.

The heater herein shown and described and claimed is shown and described in co-pending applications Serial No. 145,881, 60 filed February 1, 1917, Serial No. 153,731, filed March 9, 1917, and Serial No. 153,732, filed March 9, 1917, for method of curving the printing plates, for improvements in machine for curving printing plates, and 65 for improvements in curved printing plates.

Uses to which the heater may be applied are shown and described in said copending applications, to which reference is made.

The improved heater of the present invention may be employed for heating solid plates of metal, gutta percha, or other substances, or compositions, which when cool are 70 solids and are of such nature as to liquefy upon the application of excessive heat. 75

It is the object of the invention to provide means whereby the heat is transmitted to the body being heated by means of a molten bath of material of approximately 80 the composition or heating properties of the material of the body being heated, further, to transmit the heat of the molten bath through an intermediate support for the body being heated; further, to provide means whereby the plate being heated is pressed 85 toward its support for aiding in uniform distribution of the heat throughout the sheet, and, further, to provide means whereby to adjust the presser devices, and the invention will be further readily understood 90 from the following description and claims, and from the drawings, in which latter:

Figure 1 represents a side elevation of an 95 exemplified machine embodying the invention.

Fig. 2 is a plan view of the same.

Fig. 3 is an end view of the same, partly broken away, showing the gaging and presser means in raised positions.

Fig. 4 is an enlarged cross-section of the 100 same taken on the line 4—4 of Fig. 2, showing the gaging and presser means in depressed positions.

Fig. 5 is an enlarged vertical longitudinal section of the exemplified device, taken on 105 the line 5—5 of Fig. 2; and,

Fig. 6 is a detail in horizontal section, taken on the line 6—6 of Fig. 5, showing the

means for supporting the table in the melting pot.

The body to be heated is exemplified as a flat printing plate 21 which comprises a printing shell 23 and a backing 24, the printing shell having a printing surface on its outer face. The printing-shell and the backing may be of the materials hereinbefore mentioned, or of other materials, or 10 the object may be a different object than a printing plate but preferably of sheet form.

The margins of the printing plate are exemplified as provided with bearers 25, 26, separated from the printing surface by 15 grooves 27, 28, the bearers 25 being exemplified as at the ends of the printing plate representing its top and bottom when in the printing press, the bearers 26 being exemplified as the side bearers.

20 31 represents a table which serves as a support for the printing plate and is arranged to be heated for transmitting its heat to the printing plate for heating the latter.

25 It has been found difficult in practice heretofore to uniformly heat plates.

In the present invention the table is exemplified as partially immersed in a bath 32 in a melting pot 33, suitable means being 30 provided for heating the pot, shown as gas burners 34 formed, for instance, as perforated pipes under the pot, fed from a suitable source of supply and controlled by valves 35 discharging into gas and air mixers 36 for regulating the temperature applied to the melting pot.

The table is suitably supported in the pot. The supporting means may, for instance, be 40 lugs 38 extending upwardly from the bottom 39 of the pot. Set-bolts 40 are in threaded apertures 41 in the walls 42 of the pot, fixed in adjusted positions by jam-nuts 43. The inner ends of the set-bolts determine the lateral and lengthwise positions 45 of the table in the pot. The pot may be a part of the main frame 44 of the machine which may comprise a suitable pedestal 45 or other base for supporting the same either on a bench or on the floor, as may be desired.

50 The bath 32 is preferably of a material which is normally a solid, and is a liquid when heated to a higher temperature than the desired temperature of the material being heated. The desired temperature of the material being heated is such that when said material is subjected to the temperature for a given period, the same is rendered spongy, or of a condition hereinbefore mentioned. 60 In the case of a printing plate this desirable condition of the backing is a spongy condition, or condition to render the backing readily flowable under pressure with relation to the printing shell. The material of 65 the bath preferably has a fusing point some-

what similar to the fusing point of said material being treated, and is rendered fluid by the heat to which the melting pot is subjected.

This bath may be exemplified as a mixture 70 having a composition similar to the composition of the backing of a printing plate and may, for example, be a mixture of lead, tin and antimony in the proportion approximately of ninety pounds of lead to five 75 pounds each of tin and antimony, the fusing point of the mixture being approximately 600 degrees Fahrenheit.

The printing plate may have its printing surface presented toward the table. If desired, a flexible band 51, which may be of cold rolled steel, is interposed between the plate and the table and acts as a carrier for the plate, on which, for instance, the plate may be supported during subsequent operation, or on which the plate may be conveyed to another mechanism, and, if desired further, a cushioning layer 52, which may be a sheet of paper, may be interposed between the flexible band and the printing plate for 80 protecting the printing lines.

85 The band is suitably positioned with relation to the plate, as by having one of its edges 53 contact pins 54 adjustably placed in apertures 55 in the table, one of the ends 56 90 of the band contacting a pin 57 adjustably placed in apertures 58 in the table.

95 Means are desirably provided for adjusting the position of the plate upon the band. The plate has preferably had its edges 100 trimmed previous to having the heater act thereon, so that the end edges and the side edges of the plate are perpendicular to each other, and respectively parallel with and perpendicular to the printing lines upon the 105 plate.

110 The band is provided with a mark 61 and the plate is provided with a mark 62 which coincides with its median line. The flexible band having been adjusted on the table so that its mark 61 will be approximately in the lengthwise middle of the table and the mark 62 of the plate having been brought in registry with the mark 61, will locate the plate in substantially the middle of the 115 length of the table.

120 Gages 71 are provided for the side edges of the plate, the gages being adjustable lengthwise on arms 72 and held in adjusted positions by set-screws 73, the arms 72 being movable laterally and swingable on their bearings 74 on a rod 75 supported in brackets 76 extending from the frame of the machine. The arms are held in down position by latches 77 arranged to engage a holding-bar 78 on the frame. The arms are counter-weighted by counterweights 79 for raising the arms away from the plate when the latches 77 are released. The arms are arranged to be depressed by a handle 80. 125 130

In positioning the plate, the plate is laid on the band with the mark 62 thereon in registry with the mark 61 on the band. The arms 72 are brought downwardly and 5 latched so as to place the gages above the band and the gages adjusted so as to be equidistant from the side edges of the table and for placing the plate in substantially the middle in width of the table. The side edge 10 of the plate is then guided against the gages.

Presser means are desirably provided for pressing the plate at various points thereon toward the table and for subjecting the plate to pressure during application of the heat.

15 Such presser means are exemplified as comprising presser-feet 81 adjustable lengthwise on arms 82 and held in adjusted position by set-screws 83. The arms are shiftable on their bearings 84 laterally on the rod 75 20 and are arranged to rock on said rod. The arms and presser-feet are preferably so adjusted that the presser-feet when depressed will rest upon the rear faces of the bearers 25, 26, of the plate being heated. The arms 25 are held in down position by means of latches 87 arranged to engage the holding-bar 78. The arms 82 are arranged to be automatically raised away from the plate by counterweights 89 which automatically act to raise 30 the arms when the latches 87 are released.

When a plate of large area is operated on it is advisable to provide additional presser elements acting upon interior portions of the plate within the margin on which the presser feet 81 coat. Such additional presser elements are preferably of greater area than the presser-feet 81 in order to contact a greater area of the backing of the plate being heated to limit indentation of the same 35 when the plate is in heated condition. These latter presser means may, for instance, be presser-shoes 91 adjustable on an arm 92 and held in adjusted positions on the arm by set-screws 93, the arm being adjustable 40 on its bearing 94 lengthwise of the rod 75, and arranged to swing on said bearing on said rod. The arm is provided with a latch 97 which coats with the holding-bar 78 for holding the arm in down position. The arm 45 92 is provided with a counterweight 99 for automatically raising said arm away from the plate being heated.

The arms 72 and the arms 82, 92, are arranged to be independently moved. The 50 arms 72 are preferably raised as soon as the pressure by the presser means has been applied to the plate.

Uniform transmission of heat from the molten bath to the table and through the 55 flexible band and cushioning layer, when the latter are employed, to the plate being heated, is insured, while observation of the condition of the plate is readily permitted, as the presser-feet rest on the plate in separated 60 relations. When the plate is in proper heat-

ed condition, the latches 87, 97, are released, and the arms 82, 92, raised, so as to release the plate, which can then be further operated on or, if desired, removed from the heater, using the band as a carrying medium. 70

By means of the invention the heating of the plate is accurately accomplished uniformly throughout the plate, so as to render all its parts of uniform texture or condition and avoids excess heating of the plate in 75 spots and insufficient heating in other spots, and, for example, renders all the parts of the plate equally spongy or equally flowable under pressure, or other desired condition.

Having thus fully described my invention, 80 what I claim as new and desire to secure by Letters Patent, is:

1. In a heater of the character described, the combination of a table, a bath which is normally a solid in which said table is received with the upper surface of said table outside said bath, a melting pot in which said bath is located, means for heating said pot, and spaced-apart means for pressing a plate to be heated toward said table for 90 conveying heat to said plate while being pressed.

2. In a heater of the character described, the combination of a table, a bath which is normally a solid in which said table is received with the upper surface of said table outside said bath, a melting pot in which said bath is located, means for heating said pot, means for positioning a plate to be heated above said table, and spaced- 100 apart means for pressing said plate toward said table, and constructed and arranged for conveying heat to said plate through said table and limiting the degree of said heat.

3. In a heater of the character described, the combination of a table, a flexible carrier band arranged to be received thereon and for supporting a plate to be heated, a bath which is normally a solid in which said table is received, a melting pot in which said bath is located, means for heating said pot, and adjustable means for positioning said flexible carrier band on said table. 110

4. In a heater of the character described, the combination of a table, a flexible band arranged to be received thereon and for supporting a plate to be heated, means for heating said table, and means for positioning said flexible band on said table, said flexible band provided with positioning means for 120 the plate to be heated.

5. In a heater of the character described, the combination of a table, means for heating said table, locating gages for the plate to be heated, and means for adjustably positioning said gages above said table for gaging said plate. 125

6. In a heater of the character described, the combination of a table, means for heating said table, gages for the plate to be heated 130

adjustable above said table for positioning said plate, and adjustable presser-means above said table for pressing said plate to be heated toward said table.

5 7. In a heater of the character described, the combination of a table, means for heating said table, gages for the plate to be heated adjustable above said table for positioning said plate, adjustable presser-means 10 above said table for pressing said plate to be heated toward said table, and means for independently moving said gages and presser-means away from the position of the plate.

8. In a heater of the character described, 15 the combination of a table, means for heating said table, a flexible band, means between said flexible band and table for determining the position of said flexible band with relation to said table, and adjustable gages having coaction with the plate adjustable above 20 said table.

9. In a heater of the character described, 25 the combination of a table, means for heating said table, arms pivoted with relation to said table, gaging means and presser means respectively adjustably positioned on said arms, and means for moving said arms toward and from said table, whereby to 30 gage the position of the plate above said table and for pressing said plate toward said table.

10. In a heater of the character described, 35 the combination of a table, means for heating said table, arms pivoted with relation to said table, gaging means and presser means respectively adjustably positioned on said arms, and means for moving said arms toward and from said table, whereby to gage the position of the plate above said table and 40 for pressing said plate toward said table, said arms for said gaging means and presser means respectively being independently movable toward and from said table.

11. In a heater for printing plates, the 45 combination of a table, a flexible carrier-band thereon on which the plate to be heated is arranged to be received, a bath which is normally a solid in which said table is partially immersed, heating means for said 50 bath for melting the same, and spaced-apart presser-feet for pressing said plate and said flexible carrier-band toward said table.

12. In a heater for printing plates, the 55 combination of a table, a flexible carrier-band thereon on which the plate to be heated is arranged to be received and supported when in near-fused condition, a bath which is normally a solid in which said table is partially immersed, heating means for said 60 bath for melting the same, and spaced-apart means for pressing the plate and said fusible

carrier-band toward said table during the heating of said plate.

13. In a heater for printing plates, the combination of a support arranged for receiving a printing plate, means for heating said support, and pressing means comprising adjustable presser-parts adjustable cross-wise of said support for pressing said printing plate toward said support during the 70 heating of said printing plate.

14. In a heater for printing plates, the combination with a printing plate having bearers at its edges, a support for the same, means for heating said support, and presser 75 means for pressing said printing plate toward said support, said presser means comprising presser-parts adjustable for pressing upon said bearers of said printing plate.

15. In a heater for printing plates, the 80 combination of a support for the printing plate, means for heating said support, arms pivoted with relation to said pot, adjustable presser-parts on said arms for pressing the printing plate toward said support, latches 85 for said arms for holding said presser-parts in pressing position, and means for automatically raising said arms upon release of said latches.

16. In a heater for printing plates having 90 a backing of a given material which is normally a solid, the combination of a support for the plate, a bath which is normally a solid having substantially the same heating properties as said given material, means for 95 pressing said printing plate toward said support, and means for melting said bath, whereby heat of said bath is transferred to said backing of said printing plate through 100 said support for imparting uniform heat to said backing and controlling the near-fused condition of said plate throughout the area of said backing.

17. In a heater for printing plates having 105 edge-bearers, a support for the plate, a bath which is normally a solid receiving said support, means for heating said bath, presser-feet arranged to coact with said bearers, means for adjusting said presser-feet cross-wise of said support, and additional presser-feet arranged to act on the plate between 110 said bearers, said presser-feet being spaced apart and acting on said plate while the same is being heated by means of said bath.

In testimony whereof, I have hereunto 115 signed my name in the presence of two subscribing witnesses.
